(57) **CLAIM**

The ornamental design for a portable charging station for portable computing devices, as shown and described.

DESCRIPTION

FIG. 1 illustrates a top front perspective view of a portable charging station for portable computing devices, according to a first configuration;

FIG. 2 illustrates a front view thereof;
FIG. 3 illustrates a back (rear) view thereof;
FIG. 4 illustrates a top view thereof;
FIG. 5 illustrates a bottom view thereof;
FIG. 6 illustrates a left-side view thereof;
FIG. 7 illustrates a right-side view thereof;
FIG. 8 illustrates a different top front perspective view thereof;
FIG. 9 illustrates a top back (rear) perspective view thereof;
FIG. 10 illustrates a top and left-side perspective view thereof;
FIG. 11 illustrates a bottom and a front perspective view thereof;
FIG. 12 illustrates a front view of the portable charging station for portable computing devices, according to a second configuration;
FIG. 13 illustrates a back (rear) view of the portable charging station for portable computing devices, according to the second configuration;
FIG. 14 illustrates a top view of the portable charging station for portable computing devices, according to the second configuration;
FIG. 15 illustrates a left-side view of the portable charging station for portable computing devices, according to the second configuration;
FIG. 16 illustrates a right-side view of the portable charging station for portable computing devices, according to the second configuration;
FIG. 17 illustrates a close-up detail view of a portion of a top of the portable charging station for portable computing devices, according to the second configuration; and,
FIG. 18 illustrates a top, front, and left-side perspective view of the portable charging station for portable computing devices shown in environmental use.
The broken lines in the figures depict portions of the portable charging station for portable computing devices that form no part of the claimed design; and the smartphone, the light, and the speaker drawn in broken lines in FIG. 18 also form no part of the claimed design.
